METALLIC JAR

John H. Kjellstrom, Rockford, Ill., assignor to
 J. L. Clark Manufacturing Co., Rockford, Ill.,
 a corporation of Illinois

Application November 12, 1934, Serial No. 752,619

9 Claims. (Cl. 220—10)

The invention pertains to small metallic jars of the type especially suited for use as a container for cold cream, ointments and the like, and usually made of glass or similar materials.

5 The primary object of the invention is to provide a jar or container of the character indicated, which is constructed of sheet metal, and which combines the advantages of lightness in weight and attractiveness in appearance with a 10 novel and advantageous construction, such that the interior surface is entirely free from joints or crevices and an outer surface devoid of sharp or raw edges.

A further object is to provide a metallic jar 15 or container of the character indicated, which is of advantageous construction such that a low cost of manufacture is attained.

The objects of the invention thus generally stated together with other and ancillary advantages, are attained by the construction and arrangement illustrated in the accompanying drawings forming part hereof, wherein:

25 Figure 1 is a perspective view of my improved jar or container.

Fig. 2 is a central vertical sectional view through the container.

25 Fig. 3 is a similar view showing a modified construction.

In carrying out my invention, I employ a double walled construction for the container comprising inner and outer shells spaced apart to form a narrow annular air space between them and having their upper end portions coacting to form a neck of reduced diameter adapted to receive the skirt of a closure cap, and to provide an entirely smooth inner surface and an outer surface lending itself to attractive decoration and avoiding exposed sharp or rough edges.

35 Referring now to Figs. 1 and 2 of the drawing, a preferred embodiment of the invention comprises spaced outer and inner shells 7 and 8 with their upper end portions coacting to form a neck 9 of reduced external diameter. The container is closed by a cap or cover 10 having a 40 depending skirt 11 fitting over the neck 9.

The outer shell 7 is made from flat sheet metal of relatively light gauge and comprises a vertical peripheral side wall 12 preferably cylindrical in form. A flat bottom wall 13 in the form of a disk fits snugly within the lower end portion of the peripheral side wall and rests upon the upper edge of an inwardly and upwardly curled flange 14.

45 The inner shell 8 is preferably drawn from a flat sheet of metal to provide a peripheral side

wall 15 and a bottom wall 15a. As herein shown, the bottom wall 15a of the inner shell rests upon the bottom wall 13 of the outer shell although it will be apparent that the latter wall may, if desired, be dispensed with in which event the inner shell may engage directly with the flange 14 of the outer shell.

A feature of primary importance in the provision of a container for receiving cold creams, ointments and the like is the construction employed in forming the neck 9. This construction comprises in the present instance a reduced upper end portion 16 on the outer peripheral side wall 12, and a flange 17 formed at the upper end of the inner side wall 15. The latter abuts 15 the extreme upper edge of the reduced portion 16 and is thence folded downwardly thereover to form a smooth and relatively wide collar 17a for the neck and at the same time serving to unite the two shells in an interlocking seam. 20

In forming the reduced upper end portion 16 of the outer shell, an upwardly facing shoulder 18 of substantial radial width is formed, and the flange 17 is made of a width such that the free edge of the collar 17a formed thereby abuts 25 the shoulder 18. Thus the shoulder effectually covers the lower free edge of the collar 17a thereby serving to prevent injury to the hand of the user.

30 Outwardly of the collar 17a the shoulder 18, 30 because of its substantial width, opposes the lower end of the cap skirt 11 which may thus be disposed substantially in the plane of the outer side wall 12. Preferably, the lower edge of the skirt 11 is curled as indicated at 19 so as to conceal the sharp edge of the metal. Also, as will be evident, this curled edge of the skirt forms a 35 projecting bead facilitating the removal of the cover.

35 By the construction thus employed, the two 40 shells are firmly secured together, the interior of the container is of substantially uniform diameter from top to bottom, and the inner surface entirely devoid of seams, crevices, joints or rough edges, while the upper end of the container terminates in a smooth rounded edge. Externally of the container, sharp or rough edges are effectually concealed, and when the cap or cover is in position the container is of substantially uniform diameter from top to bottom with the exception of the bead 19. Finally, a narrow insulating dead air space 20 is formed between the two shells which space is closed at its upper end by the shoulder 18 and at its lower end by the bottom wall 13 of the outer shell. 50 55

The cap 10 may be made from a flat sheet of metal drawn to provide the depending skirt 11. Preferably, the top of the cap is formed with a slight upward bulge, and within the cap is fitted 5 a flat liner 21 engageable near its peripheral edge with the upper rounded edge of the neck 9. Due to the bulge in the top wall of the cap, an insulating dead air space 22 is formed within the cap.

In Fig. 3 of the drawing, a slightly different embodiment of the invention is illustrated. In this instance, the neck of the container, while constructed in the manner above set forth in connection with Fig. 2, is formed with screw threads as indicated at 23, and the skirt of the cap correspondingly threaded as at 24, so that the cover may be screwed into position. It will be observed that the screw threads 23 are formed through the three thicknesses of material constituting the neck.

20 In this latter embodiment, the bottom construction of the container is also somewhat different. Thus, the bottom wall 25 of the outer shell is formed with a peripheral flange united by means of a seam 26 with the lower end portion 25 of the outer wall of the container.

It will be observed that I have provided a sheet metal container of a very practical character, especially adapted for use as a container for creams, ointments and the like. Such a container is especially advantageous as compared to the commonly used glass jars in that it is light in weight, which is a material advantage in the case of foreign shipments, and in that it is not subject to breakage either when the container 35 is accidentally dropped or when removing the cover. The sheet metal construction furthermore lends itself readily to attractive decoration in that the outer metallic surfaces may be readily lithographed, and moreover, because of the construction 40 employed, the container presents a neat and attractive appearance.

I claim as my invention:

1. A container of the class set forth comprising inner and outer shells having peripheral side 45 walls of sheet metal spaced apart to form a narrow annular space between them, said inner shell being of substantially uniform diameter from top to bottom and having a wide flange at its upper end, and said outer shell having an integral upper end portion of reduced diameter fitting snugly 50 about the upper end portion of the inner shell and forming an upwardly facing shoulder spaced a substantial distance below the upper end of the inner shell, said flange on the inner shell being folded around the upper edge of said reduced end portion of the outer shell and downwardly with its free edge adjacent said shoulder so as to form 55 a collar of substantial width, and a cap having a skirt fitting over said collar with its lower edge terminating adjacent said shoulder.

2. A container of the class set forth comprising inner and outer shells having peripheral side walls of sheet metal spaced apart to form a narrow annular space between them, said inner shell being of substantially uniform diameter from top to bottom and having a wide flange at its upper end, and said outer shell having an integral upper end portion of reduced diameter fitting snugly 60 about the upper end portion of the inner shell and forming an upwardly facing shoulder spaced a substantial distance below the upper end of the inner shell, said flange on the inner shell being folded around the upper edge of said reduced end portion of the outer shell and downwardly with 65

its free edge adjacent said shoulder so as to form a collar of substantial width, and a cap having a skirt fitting over said collar and disposed substantially in the plane of the outer shell below said surface, and an outwardly projecting bead 70 formed at the free edge of the skirt adjacent said shoulder.

3. A container of the class set forth comprising inner and outer shells having peripheral side walls spaced apart to form a narrow annular space between, said inner shell being made from a single sheet of metal to form a bottom wall and said inner side wall of substantially uniform internal diameter from top to bottom and having a wide flange at its upper end bent outwardly 10 and downwardly to form an integral collar of substantial width, and said outer shell having an upper end portion bent inwardly with its free edge covered by the collar and providing an upwardly facing external shoulder adjacent the 15 lower end of the collar, and a cap having an annular skirt fitting over said collar and terminating adjacent said shoulder.

4. A container of the class set forth comprising inner and outer shells having peripheral side 20 walls spaced apart to form a narrow annular space between, said inner shell being formed from a single sheet of metal to provide the inner peripheral side wall and having a wide flange at its upper end bent outwardly and downwardly 25 to form an integral collar of substantial width, and said outer shell having an upper end portion bent inwardly and having its free edge covered by the collar and forming an upwardly facing 30 external shoulder adjacent the lower end of the collar, and a cap having an annular skirt fitting over said collar and terminating adjacent said shoulder with a skirt disposed substantially in the plane of the outer side wall below said shoulder.

5. A container of the class set forth comprising inner and outer shells having peripheral side walls spaced apart to form a narrow annular space between, said inner shell being formed from a single sheet of metal and having a side flange 45 at its upper end bent outwardly and downwardly to form an integral collar of substantial width, and said outer shell having an upper end portion bent into interfitting engagement with the collar so that its free edge is covered thereby and 50 forming an upwardly facing external shoulder adjacent the lower end of the collar, and a cap having an annular skirt fitting over said collar and terminating adjacent said shoulder with the skirt disposed substantially in the plane of the outer side wall below said shoulder, said outer side wall having means at its lower edge for closing the lower end of said annular space.

6. A container of the class set forth comprising inner and outer shells formed of sheet metal and having peripheral side walls spaced apart to form a narrow annular space between, the inner side wall being of a substantially uniform diameter from top to bottom and having a wide flange at its upper end bent outwardly and downwardly to form an integral collar of substantial width, and said outer shell having an upper end portion bent into interfitting engagement with the collar and forming a shoulder adjacent the 65 lower end of the collar, and a cap having an annular skirt fitting over said collar and terminating adjacent said shoulder with the skirt disposed substantially in the plane of the outer side wall below said shoulder, said outer side wall 70

having its lower edge portion bent inwardly at the bottom of said annular space.

7. A container of the class set forth comprising inner and outer shells with peripheral side walls spaced apart to form a narrow annular space between them, said inner shell being formed of sheet metal and having its upper end bent outwardly and downwardly to form an integral collar of substantial width, and the peripheral side wall of the outer shell having an upper end portion encircled by the collar whereby to enclose the upper free edge of the outer shell, and a cap having an annular skirt fitting over said collar and disposed substantially in the plane of the outer side wall below the collar.

8. A container of the class set forth comprising inner and outer shells with peripheral side walls spaced apart to form a narrow annular space between them, said inner shell being formed of sheet metal and having its upper end portion bent outwardly and thence downwardly to form

an integral collar of substantial width, and the peripheral side wall of the outer shell having an upper end portion disposed between the collar and the peripheral wall of the outer shell, a cap having an annular skirt fitting over said collar, and means closing said annular space at the bottom of the container.

9. A container of the class set forth comprising inner and outer shells with peripheral side walls spaced apart to form a narrow annular space between them, said inner shell being formed of sheet metal and having its upper end bent outwardly and downwardly to form an integral collar of substantial width, and the peripheral side wall of the outer shell having an upper end portion bent inwardly into engagement with the inner shell and forming a shoulder adapted to protect the free edge of the collar, and a cap having an annular skirt fitting over said collar.
